SAMUEL C. GOODSELL, OF NEW HAVEN, CONNECTICUT.

Letters Patent No. 66,079, dated June 25, 1867.

IMPROVEMENT IN HOISTING DEVICE.

The Schedule referred to in these Letters Patent and making part of the same.

TO WHOM IT MAY CONCERN:

Be it known that I, SAMUEL C. GOODSELL, of New Haven, in the county of New Haven, and State of Connecticut, have invented certain new and useful improvements in Hoisting Apparatus; and I hereby declare the following to be a full, clear, and exact description of the same, reference being had to the accompanying drawings, in which—

Figure 1 is a side elevation of my improved apparatus, and

Figure 2 an end elevation of the same looking toward the larger winding-cylinder B.

Figures 3 and 4 are plan views, showing the mechanism for throwing the truck-wheels in gear with the driving mechanism in two positions; and

Figure 5 is a section of the apparatus on the line $z z$, fig. 3.

My principal object in the invention, the subject of this application, is to produce a hoisting machine or apparatus in which the power may be greatly increased without complicating the machine, and, further, to so arrange the mechanism as to fit the machine for use either as a stationary "hoister" or as a movable apparatus by which the same result may be effected as by the use of the ordinary freight-crane with a swinging or traversing arm.

The principle upon which my invention is based is that which in mechanics is illustrated by the differential wheel and axle. I take two drums, whether conical or cylindrical in shape, and mount them side by side in a suitable frame. These drums may be either of different diameters united by gears of equal diameters, or of equal diameters connected by gears of unequal diameters, or both cylinders and gears may be of unequal diameters. The gears are mounted on their respective drums, one meshing with the other; and as under this arrangement the drums when put in motion will revolve in opposite directions, the hoisting rope or chain by which the weight is held in suspension will roll off one drum while it is wound upon the other. As the gears and cylinders revolve in opposite directions, and as the rope is suspended from the same side of each cylinder, the weight will be brought upon the gears at their point of contact, pressing them together in such manner that when the cylinders and their gears cease to revolve the weight will be held suspended in any position, (except when the difference between the diameters of the drums is sufficient to overcome the friction of the working parts.) Conical drums instead of cylinders may be employed, their bases being mounted in opposite sides of the frame, and by this means the leverage may easily be increased to any extent desired.

In order to admit of the movement of the apparatus from one point to another, carrying at the same time the weight in suspension, I mount the cylinders or drums on truck-wheels which run on a tram-way elevated to any desired height, and of such length and proportions as are required by the position and size of the wheels, and the distance or space to be traversed. These wheels are arranged so as to be thrown in and out of gear with the winding-cylinders, and thus either to remain stationary or to receive motion from the same power which rotates the drums. By this combination of parts the truck-wheels may be rotated and the apparatus moved in either direction simultaneously with the revolution of the winding-cylinders, (the latter serving not only to hoist or lower the weight, but to impart motion to the wheels,) or the wheels and apparatus may remain stationary or be moved independently of the cylinders, as occasion requires.

To enable others skilled in the art to understand and use my invention, I will now proceed to describe the manner in which the same is or may be carried into effect by reference to the accompanying drawings.

As there represented, the drums upon which the rope is wound consist of two cylinders A B of unequal diameters, supported side by side and parallel with each other, in suitable bearings formed in the sides of the machine, and geared together by means of two toothed wheels C D of equal diameters, mounted respectively upon the cylinders A B. The cylinders are revolved by means of a crank or a chain-wheel, E, on the shaft of the cylinder A, or, if more power be required, by means of an auxiliary wheel, E', carrying a pinion, F, which meshes with a toothed wheel, G, on the shaft of cylinder A. The rope H from which the weight is suspended is attached to the cylinders, one of its ends being secured at or near one of the ends of the small cylinder. After winding the rope around this cylinder until it is full, the other end is attached to the opposite end of the larger cylinder, leaving a length of rope hanging between the cylinders equal to double the "hoist" or double the distance of the cylinders from the ground, and half of the circumference of the movable pulley K around which the rope is passed before it is secured to the larger cylinder. The rope hangs from the same side of each

cylinder, as, for instance, from the side *a* of the cylinder A, and the corresponding side *b* of the cylinder B, so that as the cylinders by being geared together, as above described, are caused to revolve in opposite directions, when the rope is rolled off the smaller cylinder it will be wound upon the larger one, the weight in each revolution being raised a distance equal to half the difference between the circumferences of the two cylinders. By reversing the movement of the cylinder, the weight will, of course, be lowered in a corresponding degree. As the rope hangs from the corresponding sides *a* *b* of each cylinder, the tendency of the weight when the apparatus is not in motion is to draw the cylinders in the same directions, *i. e.*, to cause the cylinder A to revolve toward the side *a*, and the cylinder B toward the side *b*. Pressure will therefore be induced at the point of contact of the gears C D, and they will be firmly locked so as to hold the weight suspended.

The mechanisms thus far described, consisting of the differential cylinders, gears, rope and pulley, and crank or wheel, and frame in and by which the same are supported, constitute in themselves a perfect hoisting apparatus, which, where only a stationary apparatus is required, possess all the requisite qualifications or properties for such a machine. But when the apparatus is required not only to lift weights, but to move or transport them from one point to another, then additional mechanism is needed. In order to induce the apparatus with this property I mount it upon truck-wheels, which rest upon an elevated tram-way, W, or other suitable ways for holding and guiding the wheels which can be traversed by the apparatus. The shafts of one or both of the cylinders have their bearings in the hubs of the truck-wheels L L' M M', which in their turn have their bearings in the main frame V of the apparatus. The shaft of the cylinder A projects through the wheels L L' on each side, and carries on one end the driving-wheel E, on the other the toothed wheel G. Both of these wheels, while they revolve with the shaft, are capable of sliding longitudinally upon it, and they carry on their inner faces clutches *c* *c'*, which are intended to engage with the clutches *d* *d'* formed on the exterior faces and around the hubs of the wheels L L'. The pinion F of the wheel E', it may be here remarked, is of such length as to allow the wheel G to slide in the manner above described without being thrown out of gear with the same. By sliding the wheels E and G toward or away from the truck-wheels, the clutches *c* *c'* *d* *d'* are thrown in gear, so as to cause the truck-wheels to revolve in unison with the cylinders, or are disconnected so as to admit of the truck-wheels and consequently the whole apparatus being stationary while the rope is wound upon the cylinders.

The mechanism I employ for operating the clutches *c* *c'*, consists of a vibrating arm or lever, *f*, pivoted at *m* to the main frame V, and carrying two lateral arms *g* *g'*, one pivoted to the end of the lever beyond the pivotal point *m*, the other secured in like manner to the lever on the opposite side of the joint *m*. The arm *g* is fastened to the sliding-wheel E and its clutch *c*, and the corresponding arm *g'* on the other side is fastened to the toothed wheel G and its clutch *c'*. Consequently when the lever *f* is in the position shown in fig. 3, the wheel E will be drawn by the arm or lever *g* toward the truck-wheel L, so as to cause the clutches *c* *d* to engage with each other, and the arm *g'* will actuate its wheel G in like manner, causing the clutches *c'* *d'* to be thrown into gear. Now, if the lever *f* be vibrated or moved in the opposite direction, so as to occupy the position shown in fig. 4, the wheels E and G will be moved away from the truck-wheels L L', and the clutches *c* *c'* *d* *d'* will be thrown out of gear. When the apparatus is elevated upon the way W to a considerable height, the lever *f* may be operated by means of ropes *r* passing over pulleys or friction-rollers *p* in opposite side of the frame, as shown in fig. 2.

After the foregoing description, the method of operating the apparatus will be readily understood with but little further explanation.

The weight is raised and lowered by turning the wheel E, or, if greater power be required, the wheel E' in the proper direction. The upward or downward motion of the weight is, of course, differential, depending upon the difference between the diameters of the two cylinders on their gear. If at any time during the lifting or lowering of the weight the cylinders cease to revolve, the weight is maintained stationary and in suspension by reason of the arrangement of the cylinders and hoisting rope, as above explained, which throws the pressure of the weight upon the gears at their point of contact, and thus effectually locks them. During the revolution of the cylinders, if it is desired to move the apparatus to a different location, the lever *f*, which we will suppose to have been in the position shown in fig. 4, is moved to the position shown in fig. 3, so as to throw the clutches *c* *d* *c'* *d'* in gear. When this is done, the motion of the cylinder-shaft A is imparted to the truck-wheels L L', which begin to revolve, (the wheels M M' following their movement,) and move the apparatus along the way W at the same time that the hoisting or lowering of the weight is continued. When the apparatus has traversed the tram-way the desired distance, the clutches are unlocked by moving the lever *f* in the other direction, and the truck-wheels being now disconnected from the cylinder cease to move, stopping the motion of the apparatus without trouble.

It will be, of course, understood that power may be applied in various way to actuate the winding-cylinders, and by various means, whether by the employment of chain-wheels, cranks, or gearing. The proportion which the cylinders bear to each other, with respect to size and dimensions, may, of course vary, to increase or lessen the differential motion, and, as above said, they can be either conical or cylindrical in form. The gearing F G may also be combined with additional gear, so as to increase to any desired extent the power by which the cylinders are revolved.

Having described my invention, and the manner in which the same is or may be carried into effect, I shall now state my claim as follows:

1. A hoisting apparatus in which the cylindrical or conical winding-drums, whether of the same or of unequal diameters, are combined with the hoisting rope and pulley and gears under the arrangement set forth, so that the weight shall be raised or lowered with a differential motion.

2. The combination of the conical or cylindrical winding-drums and their gears, of the hoisting rope attached to said drums under the arrangement herein described, so that when the drums are not caused to rotate by their operative mechanism the weight suspended from the said rope shall cause the locking of the gears as set forth.

3. The combination, in an apparatus such as described, of the winding-drums or cylinders and their gears, with the mechanism for rotating the same arranged and operating as herein shown and specified.

4. I claim the combination, in an apparatus, as described, of the winding-cylinders, and mechanism for revolving the same, with the truck-wheels upon which the said apparatus is mounted, under such an arrangement that by the movement of the cylinders the said wheels may be rotated and the apparatus moved in either direction, as set forth.

5. The combination, with the truck-wheels, winding-cylinders, and mechanism for revolving the same, of the clutches for throwing said wheels in and out of gear with said cylinders and driving mechanism, substantially as shown and specified.

In testimony whereof I have signed my name to this specification in the presence of two subscribing witnesses.

SAMUEL C. GOODSELL.
